UNITED STATES PATENT OFFICE.

GUSTAVE M. GOLDSMITH AND CARL BARTELS, OF HAMILTON, OHIO, ASSIGNEES TO THE MOSLER SAFE COMPANY, OF HAMILTON, OHIO, A CORPORATION OF NEW YORK.

SAFE CONSTRUCTION.

Application filed April 4, 1924. Serial No. 704,115.

To all whom it may concern:

Be it known that we, GUSTAVE M. GOLDSMITH and CARL BARTELS, citizens of the United States, residing at Hamilton, in the county of Butler and State of Ohio, have invented certain new and useful Improvements in Safe Constructions, of which the following is a specification.

This invention relates to safe construction, and more particularly relates to burglar-proof safe doors made up of a plurality of plates or sections secured together, one or more of the plates or sections having special characteristics, such as being highly 10 resistant to drills, or to torches, or the like; and the principal object of our invention is to provide a construction for safe doors in which these plates and sections are secured and held together in such a way that 15 the structure is thoroughly proof against penetration and entry by means of a torch and drill, or the like, and in which the plates or sections are held securely and firmly against bodily removal under attack. A 20 further object of our invention is to provide a safe door construction in which material having special characteristics, such as being highly resistant to drill or torch, or to both, is so incorporated that it is substantially 25 coextensive with the structure to render special protection across the entire area thereof. Other objects of our invention will 30 be in part obvious and in part pointed out hereinafter.

35 This application is an improvement on the construction shown in an application filed by us February 5, 1924, Serial Number 690,723, for improvements in safe construction, the present application being directed 40 to certain more or less specific improvements.

In order that a clearer understanding of our invention may be had, attention is hereby directed to the accompanying drawings, 45 forming a part of this application, and illustrating certain possible embodiments of our invention.

Referring to the drawings, Fig. 1 is a diagrammatical front view of a safe door; Fig. 50 2 is a perspective view of a section of the door, the door being shown broken away step by step to more clearly show the construction; and Fig. 3 is a sectional view of the door. Similar reference characters refer

to similar parts throughout the several 55 views of the drawings.

Referring to the drawings, there is shown in Fig. 1, a safe door 1 and its vestibule 2, the door being supported by the usual crane hinge 3. As shown, a metal section 4 (which 60 may be a casting of suitable material, such as steel,) constitutes the body of the door and includes the front and jamb portions and the outer bolt frames 5. Section 4 has a central cavity, as shown, the side walls of 65 which are stepped inwardly toward the front of the door to form shoulders which abut against plates seated in the cavity. In the cavity are placed a plurality of plates which extend in the plane of the door, and 70 at least one of these plates is preferably of material having special characteristics, such as being highly resistant to drill or torch, or to both drill and torch, which is preferable. A plurality of plates 6, of suitable 75 material, which may be openhearth steel, are placed in the front portion of the cavity, and may be secured to the body 4 and to each other by suitable screws, such as 7. In the cavity and immediately behind plates 80 6 is a plate 8 of material having special characteristics, such as high drill or torch resistance, or both. The body 4 may be formed to have shoulders or ledges 9 which abut the forward edge portions of section 85 8. Section 8 is held in place by means of one or more key strips 10 which are seated in a recess or groove 11 provided therefor in the body 4, and which extend beyond the 90 rear edge portions of the section 8. The key strip or strips 10 are preferably of material having special characteristics, such as being highly resistant to drill or torch, or to both. Also to the rear of section 8 there may be 95 placed in the cavity a plurality of other plates 12 of suitable material, such as openhearth steel, and these plates may be secured together with suitable screws, such as 13. These plates, however, may be of material 100 having the special characteristics, such as high drill or torch resistance. The rear most of these plates 12 may overlap the key strip or strips 10 on the rear, and if the key strip is of suitable material, the plate 105 and strip may be secured together by a screw 14. The inner bolt frames 15 for bolts 16 may, if desired, be formed integral with

this rear steel plate. It will be noted that the section 8 has no screws in it and at the same time it is held in place securely and firmly against removal either rearwardly or 5 forwardly.

Preferably, the body 4 is formed with a groove 17 extending completely about its jamb portion, and one or more strips 18 of material having special characteristics, 10 such as high resistance to drill or torch, or preferably to both, are fitted into this groove, but leaving enough of the groove vacant at its outer end to enable one or more strips 19 of suitable material, such as 15 copper, to be positioned in this part of the groove to cover the strips 18 of the special material and to hold them in position. A lip or flange 20 may be formed in body 4 at the outer edge of groove 17 to aid in 20 retaining the strips 19 and 18 in place in the groove. Preferably, the strips 10 and 18 extend into the jamb portions of body 4 sufficient distances to overlap each other, with the result that the jamb portions of 25 the body 4 incorporate material having the special characteristics extending substantially across these jamb portions in the plane of the door. The plate 8 extends across the door portion between the jamb 30 portions, and thus the door incorporates the special material substantially coextensively in its plane and presents extremely high resistance to penetration by drill and torch at every point.

35 As many changes could be made in the above construction and as many apparently widely different embodiments of this invention could be made without departing from the scope thereof, it is intended that 40 all matter contained in the above description or shown in the accompanying drawings shall be interpreted as illustrative and not in a limiting sense.

What we claim is:—

- 45 1. In safe construction, in combination, a metallic body constituting a front portion and jamb portions and having a central cavity, a metallic plate in the forward portion of said cavity, a section of material having special characteristics, highly resistant to drill or torch or to both, in said cavity to the rear of said plate, a strip of material seated in an interior groove provided therefor in said body and extending beyond said groove and overlapping and abutting the rear edge portions of said section, whereby said section is held in place in said cavity.
- 50 2. In safe construction, in combination, a metallic body constituting a front portion and jamb portions and having a central cavity, a metallic plate in the forward portion of said cavity, a section of material having special characteristics, highly resistant to drill or torch or to both, in
- 55 3. In safe construction, in combination, a metallic body having a central cavity, a plurality of metallic plates seated in the forward portion of said cavity, a section of material having special characteristics, highly resistant to drill or torch or to both, 75 seated in said cavity directly behind said plates, a strip of material seated in a groove provided therefor in said body and extending beyond said groove and overlapping and abutting the rear edge portions of said section, and another plate seated in said cavity against the rear of said section.
- 60 4. In safe construction, in combination, a metallic body having a central cavity, a plurality of metallic plates seated in the forward portion of said cavity, a section of material having special characteristics, highly resistant to drill or torch or to both, 80 seated in said cavity directly behind said plates, a strip of material seated in a groove provided therefor in said body and extending beyond said groove and overlapping and abutting the rear edge portions of said section, and a plurality of other metal plates seated in said cavity directly behind said section, one of said plates overlapping and 85 abutting the rear of said strip.
- 65 5. In safe construction, in combination, a metallic body having a central cavity, a plurality of metallic plates seated in the forward portion of said cavity, a section of material having special characteristics, highly resistant to drill or touch or to both, seated in said cavity directly behind said plates, said body having shoulders overlapping and abutting the forward edge portions of said section, a strip of material seated in a groove provided therefor in said body and extending beyond said groove and overlapping and abutting the rear edge portions of said section, and a plurality of other metal plates seated in said cavity directly behind said section, one of said plates overlapping and 90 abutting the rear of said strip.
- 70 6. In safe construction, in combination, a metallic body having a central cavity, a plurality of metallic plates seated in the forward portion of said cavity, a section of material having special characteristics, highly resistant to drill or touch or to both, seated in said cavity directly behind said plates, said body having shoulders overlapping and abutting the forward edge portions of said section, a strip of material seated in a groove provided therefor in said body and extending beyond said groove and overlapping and abutting the rear edge portions of said section, and a plurality of other metal plates seated in said cavity directly behind said section, one of said plates overlapping and 95 abutting the rear of said strip.
- 75 7. In safe construction, in combination, a metallic body constituting a front portion and jamb portions and having a central cavity, a metallic plate in the forward portion of said cavity, a section of material having special characteristics, highly resistant to drill or torch or to both, in said cavity to the rear of said plate, a strip of material seated in an interior groove provided therefor in said body and extending beyond said groove and overlapping and abutting the rear edge portions of said section, whereby said section is held in place in said cavity, an exterior groove around the outside of the jamb portion of said body, and material having special characteristics, highly resistant to drill or torch or to both, seated in said groove.
- 80 8. In safe construction, in combination, a metallic body constituting a front portion and jamb portions and having a central cavity, a metallic plate in the forward portion of said cavity, a section of material having special characteristics, highly resistant to drill or torch or to both, in

said cavity to the rear of said plate, a strip of material seated in an interior groove provided therefor in said body and extending beyond said groove and overlapping and abutting the rear edge portions of said section, whereby said section is held in place in said cavity, and another plate seated in said cavity against the rear of said section.

9. In safe construction, in combination, 75 a metallic body having a central cavity, a plurality of metallic plates seated in the forward portion of said cavity, a section of material having special characteristics, highly resistant to drill or torch or to both, 80 seated in said cavity directly behind said plates, a strip of material seated in a groove provided therefor in said body and extending beyond said groove and overlapping and abutting the rear edge portions of said section, and a plurality of other metal plates seated in said cavity directly behind said section, one of said plates overlapping and 85 abutting the rear of said strip.

10. In safe construction, in combination, a metallic body having a central cavity, a plurality of metallic plates seated in the forward portion of said cavity, a section of material having special characteristics, highly resistant to drill or touch or to both, seated in said cavity directly behind said plates, said body having shoulders overlapping and abutting the forward edge portions of said section, a strip of material seated in a groove provided therefor in said body and extending beyond said groove and overlapping and abutting the rear edge portions of said section, and a plurality of other metal plates seated in said cavity directly behind said section, one of said plates overlapping and 90 abutting the rear of said strip.

11. In safe construction, in combination, a metallic body constituting a front portion and jamb portions and having a central cavity, a metallic plate in the forward portion of said cavity, a section of material having special characteristics, highly resistant to drill or torch or to both, 95 seated in said cavity directly behind said plates, said body having shoulders overlapping and abutting the forward edge portions of said section, a strip of material seated in a groove provided therefor in said body and extending beyond said groove and overlapping and abutting the rear edge portions of said section, whereby said section is held in place in said cavity, an exterior groove around the outside of the jamb portion of said body, and material having special characteristics, highly resistant to drill or torch or to both, seated in said groove.

12. In safe construction, in combination, a metallic body constituting a front portion and jamb portions and having a central cavity, a metallic plate in the forward portion of said cavity, a section of material having special characteristics, highly resistant to drill or torch or to both, 100 seated in said cavity directly behind said plates, a strip of material seated in a groove provided therefor in said body and extending beyond said groove and overlapping and abutting the rear edge portions of said section, and another plate seated in said cavity against the rear of said section.

to drill or torch or to both, in said cavity to the rear of said plate, a strip of material seated in an interior groove provided therefor in said body and extending beyond 5 said groove and overlapping and abutting the rear edge portions of said section, whereby said section is held in place in said cavity, an exterior groove around the outside of the jamb portion of said body, material 10 having special characteristics, highly resistant to drill or torch or to both, seated in said groove, said material in the exterior groove and said strip in the interior groove being in overlapping relation across the 15 jamb portion of said body in the plane thereof.

7. In safe construction, in combination, a metallic body constituting a front portion and jamb portions and having a central 20 cavity, a metallic plate in the forward portion of said cavity, a section of material having special characteristics, highly resistant to drill or torch or to both, in said cavity to the rear of said plate, a strip of material 25 seated in an interior groove provided therefor in said body and extending beyond said groove and overlapping and abutting the rear edge portions of said section, whereby said section is held in place in said cavity, 30 an exterior groove around the outside of the jamb portion of said body, material having

special characteristics, highly resistant to drill or torch or to both, seated in said groove, and other material fitted into the outer portion of said groove covering said 35 material therein.

8. In safe construction, in combination, a metallic body constituting a front portion and jamb portions and having a central cavity, a metallic plate in the forward portion of said cavity, a section of material having special characteristics, highly resistant to drill or torch or to both, in said cavity to the rear of said plate, a strip of material seated in an interior groove provided therefor in said body and extending beyond 40 said groove and overlapping and abutting the rear edge portions of said section, whereby said section is held in place in said cavity, an exterior groove around the 45 outside of the jamb portion of said body, material having special characteristics, highly resistant to drill or torch or to both, seated in said groove, and means, comprising copper fitted into the outer portion of 50 said groove, for retaining said material in 55 said groove.

This specification signed this 31st day of March, 1924.

GUSTAVE M. GOLDSMITH.
CARL BARTELS.
